Cigar Mouthpiece Holder Tip By: F.E.S.S. (Jan. 28, 2022) [https://www.2daydeliver.com/product_detail.php?id=SKUB00CLG1OME&last_node=Humidor+Accessories&click_src=googleads&gclid=\(Jul. 25, 2017\).*](https://www.2daydeliver.com/product_detail.php?id=SKUB00CLG1OME&last_node=Humidor+Accessories&click_src=googleads&gclid=(Jul. 25, 2017).)Primary Examiner — Rebecca Tsehay(74) Attorney, Agent, or Firm — Lucas & Mercanti LLP(57) CLAIM

The ornamental design for a tip for a smokable rod, as shown and described.

DESCRIPTION

FIG. 1 is a perspective view of a front, a top, and left side of a tip for a smokable rod showing my new design;

FIG. 2 is a left side view thereof;

FIG. 3 is a rear view thereof;

FIG. 4 is a front view thereof;

FIG. 5 is a right side view thereof;

FIG. 6 is a bottom view thereof; and,

FIG. 7 is a top view thereof.

The broken lines in the drawings depict portions of the tip or a smokable rod that form no part of the claimed design.
